UNITED STATES PATENT OFFICE.

CHARLES WILLIAM LA ROCHE, OF PHILADELPHIA, PENNSYLVANIA, ASSIGNOR OF
ONE-HALF TO J. NICHOLAS MEYERS, OF PHILADELPHIA, PENNSYLVANIA.

DESIGN FOR A LAMP.

59,121.

Specification for Design. Patented Sept. 20, 1921.

Application filed January 25, 1921. Serial No. 439,866. Term of patent 3½ years.

To all whom it may concern:

Be it known that I, CHARLES W. LA ROCHE, a citizen of the United States, and a resident of Philadelphia, in the county of Philadelphia and State of Pennsylvania, have invented a new, original, and ornamental Design for a Lamp, of which the following is a specification.

Reference is to be had to the accompanying drawing in which the figure is a view in elevation of a lamp showing the new design.

I claim—

The ornamental design for a lamp, as shown.

CHARLES WILLIAM LA ROCHE.
